UNITED STATES PATENT OFFICE.

FRANCIS DUVALL, OF NATIONAL MILITARY HOME, KANSAS.

DESIGN FOR A WIND-WHEEL.

SPECIFICATION forming part of Design No. 33,652, dated December 4, 1900.

Application filed August 25, 1900. Serial No. 28,083. Term of patent 7 years.

To all whom it may concern:

Be it known that I, FRANCIS DUVALL, a citizen of the United States, residing at the National Military Home at Leavenworth, in the 5 county of Leavenworth and State of Kansas, have invented and produced a new and original Design for a Wind-Wheel, of which the following is a specification.

This invention is a new and useful design 10 for a wind-wheel, the essential feature being the peculiar form of the base carrying the blades, which are also of a peculiar shape or formation.

The drawings hereto annexed fully illustrate my invention, in which—

Figure 1 is a perspective view of a wind-wheel embodying my design, and Fig. 2 is a bottom plan view of the base.

By referring to the drawings it will be seen that the base A is essentially circular in shape. 20 The base A has a series of openings C produced therein, said openings being essentially heart-shaped, and at equidistant points the blades D are mounted upon said base, said blades being constructed in the representation of a sail-boat. 25

Having thus fully described my invention, what I claim as new, and desire to secure by Letters Patent, is—

The design for a wind-wheel, substantially 30 as herein shown and described.

FRANCIS DUVALL.
